UNITED STATES PATENT OFFICE

168,111

MILK BOTTLE HOLDER

Eugene M. Navarro, New York, N. Y.

Application April 13, 1951, Serial No. 14,815

Term of patent 14 years

(Cl. D58—26)

To all whom it may concern:

Be it known that I, Eugene M. Navarro, a citizen of the United States, residing at the city, county, and State of New York, have invented a new, original, and ornamental Design for a Milk Bottle Holder, of which the following is a specification, reference being had to the accompanying drawing forming part thereof.

Figure 1 is a top view of a milk bottle holder showing my new design.

Figure 2 is a front view thereof.

Figure 3 is an end view of the same; and

Figure 4 is a top view showing the milk bottle holder as it appears in open position.

I claim:

The ornamental design for a milk bottle holder, as shown.

EUGENE M. NAVARRO.
